UNITED STATES PATENT OFFICE.

WILSON NEWMAN, OF ARDMORE, OKLAHOMA

DUSTPAN.

1,371,107.

Specification of Letters Patent

Patented Mar. 8, 1921

Application filed July 30, 1920. Serial No. 400,006.

To all whom it may concern:

Be it known that I, WILSON NEWMAN, a citizen of the United States, residing at Ardmore, in the county of Carter and State of Oklahoma, have invented certain new and useful Improvements in Dustpans, of which the following is a specification.

the following is a specification.

This invention relates to dust pans and has for its object the provision of a pan which may be manipulated without any stooping upon the part of the user and which will be of simple and inexpensive construction. The invention seeks to provide a dust pan by which a large quantity of dust and dirt may be taken up and carried from point to point without any liability of the same being accidentally discharged from the pan and at the same time facilitating the deposit of the contents when the proper place has been reached.

The invention is illustrated in the accompanying drawings and consists in certain novel features which will be particularly pointed out following a detailed description.

25 In the drawings—

Figure 1 is a perspective view of a dust pan embodying my present invention;

Fig. 2 is a longitudinal section thereof

Fig. 3 is a detailed longitudinal section showing the pan in position to receive sweepings;

Fig. 4 is a detail perspective view of the controlling springs.

In carrying out my invention, I employ a receptacle 1 which will preferably be constructed of sheet metal and is in the form of a rectangular casing or box having one open end. That wall 2 of the receptacle which, when the device is in use, rests upon the floor will be hereinafter referred to as the bottom and at the free edge thereof this wall is rolled upon itself to form a bead 3 extending entirely across the open end of the receptacle. The edges of the side walls 4 at the open end of the receptacle are preferably inclined, as shown at 4, and near the top of the receptacle notches 5 are formed in said side walls, as clearly shown. A cover 6 is provided of sheet metal having an area somewhat greater than the open end of the box and provided at its ends with wings 7 which are adapted to pass into the receptacle immediately adjacent the side walls thereof as will be readily understood upon reference to the drawings. One longitudinal edge of the cover 6 is rolled

upon itself to form a bead 8 which fits within the bead 3 upon the box so that a rolling or pivotal connection between the cover and the bottom of the box is effected. The opposite longitudinal edge of the cover 6 is protected beyond the arcuate edges of the wing 7 and is deflected slightly away from the wings, as shown at 9, whereby when the device is in position to receive sweepings, as shown in Fig. 3, the deflected portion 9 will bear closely upon the surface of the floor and serve as a skid up which the sweepings may be directed between the wings 7 and into the receptacle. Adjacent the cover 6 side arms 10, carried by a handle 11, are pivotally attached to the wings so that the cover may be readily swung from closed to open position and also the device readily carried from point to point. Passing through the inner locking rolls or beads 3 and 8 are the intermediate portions of torsion springs 12 which have their ends arranged to engage the bottom of the receptacle and the wings of the cover respectively. The end portions 13 of each spring are bent at right angles to the major portions thereof and terminate in inwardly turned points 14. Each spring has one arm 13 extended toward the bottom of the box and the terminal 14 of said arm is engaged under the bottom, as clearly shown, while the other arm 13 of the same is extended toward the free edge of the cover and its terminal 14 is engaged in an opening provided therefor in the adjacent wing 7.

It will, of course, be understood that the bottom of the pan or receptacle is engaged by the arms at opposite ends of the two springs and the same is true of the cover. As a result of this arrangement the springs act constantly to hold the cover in the closed position and in order that the cover may fit closely to the end of the pan the pivots of the side arms 10 and the terminals of the spring arms 13 are received in the notches 5 in the sides of the pan. The springs need not be very heavy but should be strong enough to hold the cover in closed position even when the pan is lifted from the floor and suspended upon the handle while being carried to a point of discharge. When dust or dirt is to be swept into the pan the receptacle is placed upon the floor, as shown in the drawings, and a slight pressure exerted thereon by the foot of the operator while the cover is pushed open against the force of the springs

by means of the handle 11. The dust and dirt may then be readily swept over the cover into the receptacle, after which, if the holding force upon the handle be released, 5 the springs will at once swing the cover to closed position so that the contents of the receptacle cannot be spilled therefrom. When the said contents are to be discharged, 10 the pan will be held in one hand while the other hand forces the cover open to permit the dumping of the dust or dirt as will be readily understood. My device is exceedingly simple in the construction and arrangement of its parts and will be found highly 15 efficient for the purpose for which it is designed.

Having thus described the invention, what is claimed as new is:

1. A dust pan comprising a receptacle 20 closed except at one end, a cover pivotally connected with the receptacle in position to close said end of the receptacle, a handle connected with the cover and free of the receptacle, and a spring concentric with the pivotal connection between the receptacle and the cover and engaging the receptacle and the cover to hold the cover normally in closed 25 position.

2. A dust pan comprising a receptacle

closed except at one end and provided with 30 notches in the edges of its sides at said open end, a cover pivotally connected with the bottom of the receptacle at the open end thereof and having wings adapted to pass into the open end of the receptacle, a spring 35 passing through the pivotal connection between the cover and the receptacle and having its ends acting upon the receptacle and the cover to hold the cover normally closed, and a handle pivotally attached to the wings 40 of the cover, the pivotal connections being so located as to pass within the notches in the sides of the receptacle when the cover is closed.

3. A dust pan comprising a receptacle 45 closed except at one end and having its bottom rolled upon itself at said end, a cover having one side edge rolled upon itself to pivotally interlock with the roll on the bottom of the receptacle, a handle pivotally 50 connected with the cover to open the same, and springs passing through the interlocked rolls on the cover and the receptacle and each having an arm at one end engaging the cover and an arm at the opposite end engaging the 55 bottom of the receptacle.

In testimony whereof I affix my signature.

WILSON NEWMAN. [L.S.]
